UNITED STATES PATENT OFFICE.

CHARLES B. WANAMAKER, OF INDIANAPOLIS, INDIANA, ASSIGNOR TO LEEDY MANUFACTURING COMPANY, OF INDIANAPOLIS, INDIANA, A CORPORATION OF INDIANA.

COLLAPSIBLE XYLOPHONE-STAND.

967,471.

Specification of Letters Patent. Patented Aug. 16, 1910.

Application filed February 26, 1910. Serial No. 546,068.

To all whom it may concern:

Be it known that I, CHARLES B. WANAMAKER, a citizen of the United States, residing at Indianapolis, in the county of Marion 5 and State of Indiana, have invented a new and useful Collapsible Xylophone-Stand, of which the following is a specification.

The object of my invention is to produce a collapsible stand especially adapted for supporting xylophones, or other similar musical instrument elements, in playing position, the structure being very light and collapsible into small compass, yet, when extended, possessing ample rigidity to sustain the musical 10 elements, though sufficiently flexible to stand firmly upon uneven surfaces.

The stand is especially useful to vaudeville performers who are compelled to carry their instruments about from town to town 15 and to set them up for use upon stages which are often rough, warped and uneven.

The accompanying drawings illustrate my invention.

Figure 1 is a perspective view of the 20 stand in expanded position ready for use; Fig. 2 a transverse section showing one expanded end in elevation; Fig. 3 a view of the parts shown in Fig. 2, in collapsed position; Fig. 4 a side elevation of the main 25 frame in collapsed condition; Fig. 5 a perspective detail showing the detachable connection between one of the supporting arms and a platform bar; Fig. 6 a longitudinal section of the parts shown in Fig. 5 when 30 said parts are assembled; Fig. 7 a vertical sectional detail of one of the collar latches; Fig. 8 a side elevation, about full size, of the 35 detachable connection between the braces between the end standards; Fig. 9 a section 40 on line 9—9 of Fig. 8; Fig. 10 a perspective view of one of the platform bars folded; Fig. 11 a fragmentary plan showing the 45 brace between two adjacent platform bars.

In the drawings, A and B indicate a pair 50 of end standards or frames which are substantially identical as to construction, though varying slightly in proportion of parts. Each of these standards comprises a central post 10 which is preferably tubular so as to be light but strong. Secured to the upper end of post 10 is a collar or cap 11 to which is pivoted, at 12, an arm 13 having a brace 15

pivoted at 16, to its outer end. Below cap 11, on post 10, is a collar 17 to which is pivoted, at 18, an arm 19 said arm being supported by a brace 21, pivoted at 22. Arranged between cap 11 and collar 17 is a collar 23 provided with an ear 24 to which is pivoted the upper end of a brace 25.

The two braces 25 are brought together 60 and pivotally connected to a pair of plates 26, 26 which are provided with a central perforation 27. The outer plate 26 is provided with a latch 28, the purpose of which will appear.

It will be readily understood that the collars 11, 17 and 23 might be formed in one piece if desired and the arrangement be such that arms 18 and 19 would be on the same level, but the arrangement shown is preferable 70 because, as will appear later, supports at two different levels are provided, as is quite common in xylophone supports.

Pivoted to the pivots 12 and 18 are the upper ends of a pair of legs 31, 31 each provided with a suitable foot 32 at its lower end. Vertically slidably on post 10 is a collar 33 to which are pivoted braces 34 which extend in opposite directions and are pivotally connected to the lower ends of legs 31.

In order to limit the downward movement of collar 33 on post 10 I provide a collar 35 at the lower end of said post, and this collar carries an ear 36 to which is pivoted the lower end of a brace 37 similar to brace 25.

The two braces 37 have their upper ends pivotally connected to a pair of plates 38, 38, and extending through these plates and secured rigidly thereto is a pin 39 adapted to be projected through openings 27 of 90 plates 26. The outer end of pin 39 is provided with a notch or groove 41 adapted to receive latch 28. The ends of braces 25 are extended beyond their pivots 42, and these extended ends lie between plates 26 so as to 95 thus stiffen the pivotal connection. It is desirable that these braces come together as closely as possible and their ends are therefore beveled, at 43, so that they will abut when brought to the position shown in Figs. 100 1 and 8, and notches 44 are provided to permit the passage of pin 39. Similarly the upper ends of braces 37 are extended between plates 38 beyond their pivots 45, and these

extended ends are beveled, as indicated by dotted lines at 46 in Fig. 4, and provided with notches to fit over pin 39 when the parts are expanded, as shown in Figs. 1 and 8.

5 In order to prevent the legs 31 from being twisted with relation to post 10, I provide the sliding collar 33 with notches 47 (Fig. 3) which, when the collar is in its lowest position, will straddle a pin 48 projecting 10 transversely from the lower end of post 10.

15 The lower ends of braces 15 and 21 are brought toward each other and pivotally connected to a sliding collar 51 mounted upon post 10 and movable downwardly from the position shown in Figs. 1 and 2 to the position shown in Figs. 3 and 4. This collar 51 is held in upper position by means of a 20 spring latch 52 pivoted at 53 within post 10 and normally urged outwardly by a light spring 54. The latch 52 is provided with a shallow notch 55 adapted to receive the lower edge of collar 51 and at this point is provided with a finger projection 56 by which it may be pressed backwardly into the interior of 25 post 10. The latch 52 is also provided with projection 57 which lies a distance above the bottom of the notch 55 equal to the vertical height of collar 51 plus a trifle more than the depth of the notch, the projection 57 30 thus preventing too great upward movement of collar 51. This arrangement facilitates the very rapid expansion of the collapsed structure, as it is impossible to carry collar 51 to a height greater than projection 57, 35 thus bringing the arms 13 and 19 to horizontal positions.

40 Each arm 13 and 19 is preferably formed of a short piece of angle iron with one arm of the angle arranged to form a horizontal ledge, and this horizontal ledge is provided with one or more perforations 61. In order to 45 form a support for the xylophone elements I provide several platform bars C which are arranged in pairs to form two rigid platforms. Of course a different horizontal support or 50 platform for the xylophone elements might be provided, but as most of these elements are flexibly connected so that they may be rolled into small compass, I deem it desirable to so form the platform bars that they may be folded into a compass which is no greater in any dimension than the collapsed main frame, as illustrated in Figs. 3 and 4. It is for this reason that the separate bars C 55 are provided. Each of these bars comprises a plate 62 the edges of which are turned up at 63 to form a channel, the upper edges being further bent inwardly to form converging lips 64. The space between portions 63 and below lips 64 may be conveniently filled 60 with a bar of light wood 65 the upper surface of which will thus form a bottom or support for a strip of felt 66 which will be held in place by the lips 64. The felt 66 65 serves as a direct support for the xylophone

elements. Each bar C is preferably formed of two parts hinged together at 67 so that it may be folded to the condition shown in Fig. 10. At each end each bar C is provided with a hook 68 having a downturned finger adapted to fit into one of the perforations 61 and, in order that each platform may be secured against accidental displacement, I provide the ends of the outer bar C of each pair with a spring bolt 69 adapted to project beneath the horizontal flange of the arm 13 or 19 and coöperate with hook 68, as clearly shown in Fig. 6. The bolt 69 is normally urged outwardly by a light spring 71, and the bolt and its spring may be conveniently mounted in a 75 folded-metal casing 72 to the upper side of which the hook 68 may be secured (as clearly shown in Fig. 6), the said casing 72 being slipped into the end of bar C and secured in place by rivets 73.

80 Hinged at 75, to either the outer or inner bar C, is a brace 76 having a notched end 77 which may be thrown behind the head 78 of a pin projecting from the adjacent face of the companion bar C, so that, when the 85 parts are assembled as shown in Figs. 1 and 11, the two companion bars C are transversely braced, one by the other.

85 With the bars in the position shown in Fig. 1 the structure may be quickly collapsed 90 in the following manner. Braces 76 will be first swung backwardly so as to withdraw hook 77 from behind head 78. Bolt 69 will then be pushed back so as to permit hooks 68 to be withdrawn from holes 61 so that the 95 outer bars C may be lifted away and folded as shown in Fig. 10. The inner bar C may then be lifted off and folded. Collars 33 may then be drawn upwardly on posts 10 and collars 51 moved upward slightly so as to 100 permit catches 52 to be pressed back into the posts whereupon they may be shoved downwardly so as to swing arms 13 and 19 downwardly toward post 10. Thereupon catch 28 may be thrown upwardly to the 105 position shown in dotted lines in Fig. 8 and pin 39 pushed (to the right Fig. 9) out of plates 26 to separate the lower ends of braces 25 from the upper ends of braces 27, whereupon plates 26 may be moved downwardly and plates 28 may be moved upwardly so that the braces 25 and 37 will collapse and the two posts 10 be brought together, as shown in Fig. 4. The parts are 110 thus very closely compacted and the bars C 115 in their folded condition may then be packed upon the collapsed frame and bound together by straps or otherwise.

120 The method of expanding the structure will be readily apparent from what has been said.

125 The braces 25 and 37 and the platform bars C serve to very rigidly connect the two end standards against any improper displacement but, nevertheless, there is suffi- 130

cient flexibility in these braces, and in the connections between the bars C and the supporting arms 13 and 19, that the four points of support provided for the feet 43 need not be in exactly the same plane, as will be readily apparent. Any inequality of this kind will, of course, result in a slight wind in the relative positions of the platform bars C but, as the zylophone elements are themselves flexibly connected, this slight wind is of no consequence. On the other hand it is very important that the supporting structure be of such character that it will be firmly positioned upon uneven surfaces.

15 I claim as my invention:

1. A collapsible xylophone stand comprising a pair of standards, a pair of downwardly extending braces pivotally connected at their upper ends to the upper ends of said standards and pivotally connected together at their lower ends, a pair of upwardly extending braces pivotally connected at their lower ends to the lower ends of said standards and pivotally connected together at 25 their upper ends, and a detachable connection between the lower ends of the upper braces and the upper ends of the lower braces.

2. A collapsible xylophone stand comprising a pair of standards, a pair of downwardly extending braces pivotally connected at their upper ends to the upper ends of said standards and pivotally connected together at their lower ends, a pair of upwardly extending braces pivotally connected at their lower ends to the lower ends of said standards and pivotally connected together at their upper ends, a detachable connection comprising a pin carried by one pair of said braces and projectable through the other pair of said braces, and a catch for holding said parts in assembled relation between the lower ends of the upper braces and the upper ends of the lower braces.

45 3. A collapsible xylophone stand comprising a pair of standards, a pair of downwardly extending braces pivotally connected at their upper ends to the upper ends of said standards and pivotally connected together at their lower ends, a pair of upwardly extending braces pivotally connected at their lower ends to the lower ends of said standards and pivotally connected together at their upper ends, a detachable connection 50 between the lower ends of the upper braces and the upper ends of the lower braces, a pair of legs pivotally connected to the upper end of each standard, and braces flexibly connected to the lower ends of said legs and the standard.

60 4. A collapsible xylophone stand comprising a pair of standards, a pair of downwardly extending braces pivotally connected at their upper ends to the upper ends of said standards and pivotally connected together

at their lower ends, a pair of upwardly extending braces pivotally connected at their lower ends to the lower ends of said standards and pivotally connected together at their upper ends, a detachable connection comprising a pin carried by one pair of said braces and projectable through the other pair of said braces, a catch for holding said parts in assembled relation between the lower ends of the upper braces and the upper ends of the lower braces, a pair of legs pivotally connected to the upper end of each standard, and braces flexibly connected to the lower ends of said legs and the standard.

70 5. A collapsible xylophone stand comprising a pair of standards, a pair of downwardly extending braces pivotally connected at their upper ends to the upper ends of said standards and pivotally connected together at their lower ends, a pair of upwardly extending braces pivotally connected at their lower ends to the lower ends of said standards and pivotally connected together at their upper ends, a detachable connection between the lower ends of the upper braces and the upper ends of the lower braces, a pair of oppositely extending arms flexibly connected to the upper end of each standard, braces flexibly connected to the outer ends of said arms and to the standard, and withdrawable means for holding the arms in extended position.

75 6. A collapsible xylophone stand comprising a pair of standards, a pair of downwardly extending braces pivotally connected at their upper ends to the upper ends of said standards and pivotally connected together at their lower ends, a pair of upwardly extending braces pivotally connected at their lower ends to the lower ends of said standards and pivotally connected together at their upper ends, a detachable connection comprising a pin carried by one pair of said braces and projectable through the other pair of said braces, a catch for holding said parts in assembled relation between the lower ends of the upper braces and the upper ends of the lower braces, a pair of oppositely extending arms flexibly connected to the upper end of each standard, braces flexibly connected to the outer ends of said arms and to the standard, and withdrawable means for holding the arms in extended position.

80 7. A collapsible xylophone stand comprising a pair of standards, a pair of downwardly extending braces pivotally connected at their upper ends to the upper ends of said standards and pivotally connected together at their lower ends, a pair of upwardly extending braces pivotally connected at their lower ends to the lower ends of said standards and pivotally connected together at their upper ends, a detachable connection between the lower ends of the upper braces and the upper ends of the lower braces,

- pair of legs pivotally connected to the upper end of each standard, braces flexibly connected to the lower ends of said legs and the standard, a pair of oppositely extending arms flexibly connected to the upper end of each standard, braces flexibly connected to the outer ends of said arms and to the standard, and withdrawable means for holding the arms in extended position.
8. A collapsible xylophone stand comprising a pair of standards, a pair of downwardly extending braces pivotally connected at their upper ends to the upper ends of said standards and pivotally connected at their lower ends, a pair of upwardly extending braces pivotally connected at their lower ends to the lower ends of said standards and pivotally connected together at their upper ends, a detachable connection comprising a pin carried by one pair of said braces and projectable through the other pair of said braces, a catch for holding said parts in assembled relation between the lower ends of the upper braces and the upper ends of the lower braces, a pair of legs pivotally connected to the upper end of each standard, braces flexibly connected to the lower ends of said legs and the standard, a pair of oppositely extending arms flexibly connected to the upper end of each standard, braces flexibly connected to the outer ends of said arms and to the standard, and withdrawable means for holding the arms in extended position.
9. A collapsible xylophone stand comprising a pair of standards, a pair of downwardly extending braces pivotally connected at their upper ends to the upper ends of said standards and pivotally connected together at their lower ends, a pair of upwardly extending braces pivotally connected at their lower ends to the lower ends of said standards and pivotally connected together at their upper ends, a detachable connection between the lower ends of the upper braces and the upper ends of the lower braces, a pair of oppositely extending arms flexibly connected to the outer ends of said arms and to the standard, withdrawable means for holding the arms in extended position, platform bars each comprising a pair of sections hinged together and each provided at its outer end with means for engaging one of the arms extending from the upper end of the standard.
10. A collapsible xylophone stand comprising a pair of standards, a pair of downwardly extending braces pivotally connected at their upper ends to the upper ends of said standards and pivotally connected together at their lower ends, a pair of upwardly extending braces pivotally connected at their lower ends to the lower ends of said standards and pivotally connected together at their upper ends, a detachable connection

comprising a pin carried by one pair of said braces and projectable through the other pair of said braces, a catch for holding said parts in assembled relation between the lower ends of the upper braces and the upper ends of the lower braces, a pair of oppositely extending arms flexibly connected to the upper end of each standard, braces flexibly connected to the outer ends of said arms and to the standard, withdrawable means for holding the arms in extended position, platform bars each comprising a pair of sections hinged together and each provided at its outer end with means for engaging one of the arms extending from the upper end of the standard.

11. A collapsible xylophone stand comprising a pair of standards, a pair of downwardly extending braces pivotally connected at their upper ends to the upper ends of said standards and pivotally connected together at their lower ends, a pair of upwardly extending braces pivotally connected at their lower ends to the lower ends of said standards and pivotally connected together at their upper ends, a detachable connection between the lower ends of the upper braces and the upper ends of the lower braces, a pair of legs pivotally connected to the upper end of each standard, braces flexibly connected to the lower ends of said legs and the standard, a pair of oppositely extending arms flexibly connected to the upper end of each standard, braces flexibly connected to the outer ends of said arms and to the standard, withdrawable means for holding the arms in extended position, and platform bars each comprising a pair of sections hinged together and each provided at its outer end with means for engaging one of the arms extending from the upper end of the standard.

12. A collapsible xylophone stand comprising a pair of standards, a pair of downwardly extending braces pivotally connected at their upper ends to the upper ends of said standards and pivotally connected at their lower ends, a pair of upwardly extending braces pivotally connected at their lower ends to the lower ends of said standards and pivotally connected together at their upper ends, a detachable connection comprising a pin carried by one pair of said braces and projectable through the other pair of said braces, a catch for holding said parts in assembled relation between the lower ends of the upper braces and the upper ends of the lower braces, a pair of legs pivotally connected to the upper ends of each standard, braces flexibly connected to the lower ends of said legs and the standard, a pair of oppositely extending arms flexibly connected to the upper end of each standard, braces flexibly connected to the outer ends of said arms and to the standard, withdrawable means for holding the arms in extended position, and platform bars each comprising a pair of sections hinged together and each provided at its outer end with means for engaging one of the arms extending from the upper end of the standard.

means for holding the arms in extended position, and platform bars each comprising a pair of sections hinged together and each provided at its outer end with means for engaging one of the arms extending from the upper end of the standard.

5 In witness whereof, I, have hereunto set

my hand and seal at Indianapolis, Indiana, this twelfth day of February, A. D. one thousand nine hundred and ten.

CHARLES B. WANAMAKER. [L. s.]
